Des. 227,437

Patented June 26, 1973

227,437

DRAWER PULL FOR CABINETS OR THE LIKE

James L. Pruitt, Great Falls, Mont.
(P.O. Box 262, Strawn, Tex. 76475)

Original design application June 18, 1970, Ser. No. 23,563. Divided and this application Oct. 25, 1972, Ser. No. 300,453

Term of patent 14 years

Int. Cl. D8—06

U.S. Cl. D8—189

FIG. 1

FIG. 2

FIG. 3

FIG. 4

FIG. 1 is a top plan view of my new design for drawer pull for cabinets or the like, the bottom plan view being a substantial mirror image thereof.

FIG. 2 is a rearward elevational view thereof.

FIG. 3 is a left end view, of FIG. 1, the right end view being a substantial mirror image thereof.

FIG. 4 is a forward elevational view thereof.

This is a division of my copending application, Ser. No. 23,563, filed June 18, 1970, now Pat. No. D. 225,306, Dec. 5, 1972.

I claim:

The ornamental design for a drawer pull for cabinets or the like, as shown and described.
